INFANT'S FEEDING NIPPLE

Joseph Prisament, Los Angeles, Calif.

Application March 19, 1956, Serial No. 40,652

Term of patent 14 years

(Cl. D83—1)

FIG. 1.

FIG. 2.

FIG. 3.

Fig. 1 is a view in side elevation of an infant's feeding nipple showing my new design;

Fig. 2 is a front view of same, and

Fig. 3 is a perspective view.

I claim:

The ornamental design for an infant's feeding nipple, substantially as shown.
